UNITED STATES PATENT OFFICE.

ULYSSES GRANT MCQUEEN, OF NEW YORK, N. Y.

CASEMENT-LIFT AND HINGE.

1,223,062.

Specification of Letters Patent. Patented Apr. 17, 1917.

Application filed April 1, 1915. Serial No. 18,608.

To all whom it may concern:

Be it known that I, ULYSSES GRANT MCQUEEN, a citizen of the United States, residing at New York, in the county of New York and State of New York, have invented certain new and useful Improvements in Casement-Lifts and Hinges, of which the following is a specification.

This invention relates to window lifts and hinges and particularly to a lift and hinge which is especially designed for use in connection with a window structure wherein the sash or casement is designed to be lifted in a vertical direction immediately prior to the time of swinging the casement in a horizontal direction for the purpose of opening the same, or at the time of lowering the casement and seating the same behind the sill stop of the window frame on re-

turning the casement to its full closed position.

The principal purpose in view in devising the above mentioned device may be stated to be that of simplicity of construction; durability, general compactness and efficiency; a device which will be positive in action, and one by which the casement with which it is associated may be expeditiously operated.

In casements of the horizontal swinging and vertically sliding type, it is customary to provide the sill with a horizontal stop-over which the casement is designed to swing after it is elevated, and behind which the casement is adapted to be seated when fully closed and in order to effect a perfect operation of the casement the combined hinge and lift is provided with means which will permit of such vertical movement of the casement as is necessary to enable the same to swing freely and not frictionally or unduly impinge against the frame or otherwise engage with the latter in any way which might hinder its freedom of movement.

The invention has for a further object, the provision of a hinge consisting of a pair of leaves, one of which being free to swing from the other but fixed against sliding movement thereon, and terminating in a branch with which is associated a lifting mechanism mounted within a housing which has fixed connection with the casement and which housing is so peculiarly formed that it will combine or coöperate with the adjacent hinge leaf to furnish therewith, a sub-

stantial brace whose function is that of holding the casement against undue sagging or assuming any other detrimental position in the frame that would interfere with the closing or opening of the casement. I further aim to connect the housing to one of the hinge leaves so that it will appear to be a continuation thereof and to also construct said housing whereby it may be readily mounted in a mortise formed in the inner face of the vertical stile of the casement and in such a manner that the mortise will be concealed by one plate thereof of said housing. In this way the housing and hinge leaves will combine to represent a complete hinge; adding materially to the attractive character of the device and to further expedite the operation of applying the device to the casement and frame.

In the drawings:—

Figure 1 is an elevation of a portion of a frame and its casement illustrating the application of the combined hinge and lift thereto and showing the casement in its normal position.

Fig. 2 is a similar view showing the casement elevated.

Fig. 3 is a horizontal section therethrough taken on the line 3—3 of Fig. 1.

Fig. 4 is a rear view of the combined hinge and lift.

Fig. 5 is a vertical section through the housing and through the lifting mechanism, showing parts in full lines.

Fig. 6 is a perspective view of the lifting eccentric and its operating handle, the latter being separated from the former.

Fig. 7 is a perspective of one of the housing sections.

Fig. 8 is a perspective view of one of the hinge leaves.

The casement A is free to move in a vertical direction in the frame B and also to swing horizontally. When the casement is closed as in Fig. 1 its base bar C rests upon the sill D and behind the stop strip E which rises therefrom. These parts may be of the usual or any other well known form and they are therefore only specifically referred to in order that the invention and its purpose can be fully appreciated or understood.

The casement herein shown opens from the left and on the left side thereof is mounted a housing 1 consisting of an outer mortise concealing plate 2 and an inner plate 3. 111

This inner plate is provided with integral upper and lower spacing flanges 4 and 5 and side combined spacing and stop flanges 6 and 7. All of these flanges rest against the inner face of the plate 2, and the latter is secured to the plate 3 by screws or equivalent fastenings 8. The side of the plate, immediately opposite the flanges 6 and 7 is open, and as illustrated in Fig. 3 the plate 3 is extended slightly beyond said open side as at 9 and then angularly as at 10. The extension 10 is rabbeted in the adjacent vertical edge of the casement and secured therein by fastening screws 11. The surface 12 of the extension 9 is disposed at right angles to the position of the adjacent vertical edge 13 of the plate 2. The surface 12 and the mentioned edge 13 of the housing plates freely bear respectively against mating surfaces 14 and 15 of the free hinge leaf 16. The housing is secured to the casement by means of screws 17. Through this construction the housing is adapted to nicely fit in a single mortise formed in the inner face of 25 the vertical stile of the casement, as illustrated in Fig. 3, and it will be made to appear as a part of a hinge structure to be referred to hereinafter.

The hinge 18 consists of the mentioned 30 free leaf 16 and a second leaf 19, the latter having fixed connection, with the frame B as at 20 and it carries three knuckles 21, 22, and 23 between which, the two knuckles 24 and 25 of the leaf 16 are interposed. Both 35 of these leaves are normally disposed within the vertical plane of the stile A of the casement so that the tongue A' of the casement can freely come in contact with the rabbeted walls B' of the frame B, as shown in Fig. 3. Through all of these knuckles a pintle 26 is 40 passed having fixed caps 27-27 as shown. This construction is such that one leaf is mounted to freely swing from the other, yet it is properly held against sliding thereon. 45 The described number of knuckles upon the respective hinge leaves have been found to give splendid results but it is desired to mention that such arrangement is not wholly essential, yet preferred for a purpose to be 50 hereinafter referred to.

The leaf 16 has an integral saddle 28 formed with branch arms 29-29 which forms a part of the lifting mechanism, whereby the housing can be moved in a vertical direction on the hinge. These arms 55 29-29 are each provided on its inner face with a hardened surface 30, preferably a steel plate and operating thereover is an eccentric 31 which forms the other part of the 60 lifting mechanism. This eccentric is interposed between the plates 2 and 3 of the housing and it is provided with a substantially U-shaped recess 32 which receives a correspondingly formed boss 33 on a revolving 65 stud 34 respectively mounted to revolve

in the plates 2 and 3. A screw 34' extends through the boss 33 and it enters the eccentric as at 35 and in this manner the latter is securely held in place upon the stud. The distance between the arms 29-29 is approximately equal to the diameter of the eccentric and as a consequence thereof it results that the housing will be moved in a vertical direction when the eccentric is rotated. The stud 34 carries an operating handle 36 which is exposed from the front plate 2 of the housing and when in the position shown in Fig. 1 the eccentric is freely interposed between the arms 29-29 and the bar C of the casement seated behind the stop strip D. 70 When the handle is in the position shown in Fig. 2 the eccentric is bearing against the lower arm 29 and the casement elevated above the stop strip, as will be understood. By simply turning the handle 36 it follows 75 that movements in an upward or downward direction will be imparted to the casement. It is desired that notice be taken of the position of the flanges 6 and 7 with relation to the axis of the eccentric. This relation of 80 the described parts is nicely shown in Fig. 4 and when the handle 36 is down the eccentric bears against the surface 37 of the flange 6. When the handle is up as shown in Fig. 85 2 the eccentric bears against the stop surface 38 of the flange 7. Through this construction, the handle can only be moved, for a limited distance with relation to the adjacent side bar of the frame B and the hand of 90 the operator is held against suddenly coming in contact with the casing, and principally and most important, through said arrangement, the casement may be accurately 95 adjusted in a vertical direction as will be seen, and when it contacts with said surface 100 38, the casement is positively free to pass over the strip D.

The plate 3 has a vertical guide slot 39 formed therein and extending therein is a lug 40 on one side of the hinge leaf 16. This 105 lug 40 and slot 39 combine with the coating surfaces 9 and 14 and 13 and 15 to brace the hinge elements in a very substantial manner and the casement is properly held against undue sagging during its swinging movement and accuracy of operation of the casement follows or is resultant from such arrangement. The lug 40 further serves to hold the housing operatively connected with the hinge. 115

The specific arrangement of the hinge knuckles 21, 22, 23, 24 and 25, when taken with the surfaces 9 and 14 and 13 and 15 is desired as it is found that the strain upon the structure is evenly distributed and the 120 several parts are satisfactorily held against breaking from one another under most trying conditions.

The mortise concealing plate 2 of the 125 housing 1 has a length approximately equal 130

to that of the hinge and from the showing in Fig. 1, the housing and the hinge will be made to appear as a single hinge structure.

Having described the invention, what is claimed is:

1. A casement lift comprising a housing mounted in a mortise in the inner side of the vertical stile of the casement and including inner and outer plates, the outer 10 plate having a continuous vertical slot, a hinge having one leaf secured to the frame and a second leaf extended between said plates and free to slide in a vertical direction and provided with spaced arms, a lug 15 extending between said arms and freely movable in said slot, and means co-acting with the arms to slide the casement vertically.
2. A casement lift comprising a housing mortised in the casement, and having a vertical slot in one of its walls, a hinge having one leaf secured to the frame and having its other leaf extending into the housing and adapted to permit the latter to slide thereon, a pair of arms carried by said other leaf, 25 a continuous lug connecting the arms with each other and freely passing into the slot, the length of the slot exceeding the length of the lug, a pair of knuckles formed on said other leaf, the frame leaf having an unequal number of knuckles thereon, a pin 30

passing through the first and second named knuckles and lifting mechanism moving the housing on said other leaf, said leaf having free contact with the housing and co-operating with said slot and lug to form a guide 35 for the housing.

3. A casement lift and hinge including parallel leaves, one of said leaves being adapted for connection with the frame, two plates adapted to be secured to the casement, 40 one of said plates being mounted in a mortise formed in the inner face of the vertical stile of the casement, the other plate being extended over the inner face of the casement to conceal the mortise and being co-extensive in length with the next adjacent leaf of the hinge and having a continuous 45 edge portion arranged in sliding contact therewith, to form a brace in the full length thereof, means on said next adjacent leaf interposed between said plates, and lifting mechanism permanently carried by said plates and co-acting with said means.

In testimony whereof I affix my signature in presence of two witnesses.

ULYSSES GRANT McQUEEN.
